[57] CLAIM

The ornamental design for a combined vehicle body cover and support housing unit, as shown and described.

DESCRIPTION

FIG. 1 is a rear elevation view of a combined vehicle body cover and support housing unit showing my new design;

FIG. 2 is a top plan view thereof;

FIG. 3 is a front elevation view thereof;

FIG. 4 is a bottom plan view thereof;

FIG. 5 is a left side elevation view thereof;

FIG. 6 is a right side elevation view thereof;

FIG. 7 is a perspective view thereof;

FIG. 8 is an enlarged cross-sectional view thereof taken along line VIII—VIII in FIG. 1;

FIG. 9 is an enlarged fragmentary sectional view thereof taken along line IX—IX in FIG. 2;

FIG. 10 is a rear elevation view thereof on a reduced scale shown mounted on the rear deck of a vehicle body; and

FIG. 11 is a left side elevation view thereof on a reduced scale shown mounted on the rear deck of a vehicle body with the cover extended in condition of use for covering the vehicle body.

The broken lines shown in FIGS. 10 and 11 of the drawing are for illustrative purposes only and form no part of the claimed design.
